G. A. ROTH,
LUGGAGE CARRIER,
APPLICATION FILED SEPT. 22, 1921.

1,431,429.

Patented Oct. 10, 1922.

UNITED STATES PATENT OFFICE.

GILBERT A. ROTH, OF HASTINGS, NEBRASKA.

LUGGAGE CARRIER.

Application filed September 22, 1921. Serial No. 502,439.

To all whom it may concern:

Be it known that I, GILBERT A. ROTH, a citizen of the United States, residing at Hastings, in the county of Adams and State 5 of Nebraska, have invented certain new and useful Improvements in Luggage Carriers, of which the following is a specification.

This invention has to do with improvements in luggage carriers adapted for attachment to the running board of motor vehicles or the like.

These improvements have been especially designed with a view to increasing the strength and durability, more particularly, 15 of devices of this character, and in this respect differs essentially from the invention set forth in my co-pending application Serial No. 417,613, filed October 18, 1920.

As in my previous invention, just mentioned, the objects more particularly subserved by this form of carrier are maximum extension without sacrifice of strength when in use, and compactness or foldability into as small a compass as possible when it is desired to ship or stow it away. To this end, 25 the present invention resides especially in the method or manner of connecting the lazy-tong structure of the device with the supporting standards and the provision of an intermediate standard connection devised to prevent sagging or bulging when carrying a heavy load.

These and such other objects as may hereinafter appear are attained by the novel construction, combination and arrangement of parts to be hereinafter specifically described and claimed.

Reference will now be had to the accompanying drawings forming a part of this 40 specification, wherein:

Figure 1 is a side elevation of a carrier constructed in accordance with my invention applied in extended position to a support.

Figure 2 is a sectional view on the line 2-2 of Figure 1, showing the end standard and gate in elevation.

Figure 3 is a sectional view on the line 3-3 of Figure 1, showing the clip connection to the end standard.

Throughout the following detailed description and on the several figures of the

drawing, similar parts are referred to by like reference characters.

Referring to the drawing, 1, 1 designate 55 end standards forming the end supports of this device, these being of corresponding form and construction. Each consists of an upright bar 2 which is bent laterally at its lower end, as indicated at 2', and secured to the upper face of a clamp 3, the upper arm 3' of which is sufficiently long to extend substantially across a running board 4 constituting a support for the device when in use. This upper arm is provided with lateral flanges 5 between which the bent base portion 2' of the standard is received, a cap screw 6 detachably connecting the standard to the clamp. The lower arm of the clamp is positioned when in use 60 below the running board and carries the clamping screw 7. A frame construction composed of the angle piece 8 and the diagonally arranged brace 9 is secured to the upper extremity of the standard and to 70 the inner extremity of the arm 3', thus forming an end gate for retaining the articles to be carried within the bounds of the luggage carrier. The end standards are connected together by a lazy-tong structure 10 which 75 is of conventional form in that it is composed of a series of pivotally connected levers capable of being extended and collapsed according to the desires of the user.

Instead of connecting the lazy-tong structure to the end standards directly, which 80 would necessitate provision for relative movement of the ends of the lazy-tong in a vertical plane and which would necessarily limit the extension of the lazy-tong below 85 that which would be desirable, I provide a special form of connection consisting of a pair of short links 11, each of which is connected at one of its ends to a lazy-tong lever and at its other end to the standard by means 90 of a clip 12. It will be observed that this 95 differs from my previous form of connection in which the links corresponding to those designated 11 are connected together and then to the standard by a common connecting clip. The advantage of the present arrangement wherein the links are connected to the standard at spaced points is that the 100 strains due to the shifting of articles carried

will be much more readily resisted, preventing the tendency to twist the connection and break the same as is likely to happen where the single point connection is utilized and the carrier overloaded. The majority of luggage carriers of this type connect the ends of the lazy-tongs directly to the extreme ends of the standard, but, as will be apparent from the drawings, I neither connect it at a single point in the center nor do I connect it at the extreme ends, but rather at points intermediate these, which gives a doubly strong arrangement capable of resisting the stresses. The loose clip connection with the standard permits the end standards to be rotated so as to bring the end gates into substantially parallel relation with the lazy-tong structure, so that the device when not in use may be folded into compact form, one end gate superposed upon the other.

The provision of the diagonal brace 9 for the end gate insures a very rigid bracing of this part, as will be quite obvious.

It will be observed that I employ in this construction a central standard, the desirability of which is quite apparent when it is realized that considerable pressure is usually exerted intermediate the length of the lazy-tong structure when this is in extended position. In the present case the central standard 13 is slightly greater in height than the end standards and is designed to be connected to the lazy-tong structure at the end points of connection of the intersecting levers of this part instead of to the intermediate connecting rivet as in my previous case. Obviously the double point connection is very much stronger than the single point connection to the standard. To permit of this connection the upright member of the standard is slotted at the top and at the bottom as indicated at 14 so as to slidably receive the rivets 15 of the connecting levers, the slotting of the standard in this manner accommodating the movement of the levers in extension and contraction of the lazy-tong structure. The clamp member at the lower end of the central standard corresponds to the general construction of the clamp members for the end standards excepting that it is not provided with a long upper arm.

It will be obvious that a carrier constructed in accordance with the foregoing will present a very rigid resistance against the tendency to bulge outwardly when the capacity of the carrier is crowded, and the use of the central standard support effectively prevents any sagging of the lazy-tong structure regardless of the amount of extension which is given thereto within the limits of the possible extension.

Having thus described my invention, what I claim as new and desire to secure by Letters Patent is:

1. In a luggage carrier of the type described, end standards, means for clamping each standard to the running board of a vehicle, a lazy-tong structure intermediate the standards, and means to connect the lazy-tong structure with the standards comprising a pair of links pivotally connected to each end of the lazy-tong structure, and a clip pivotally connected to the end of each link and loosely connected to the adjacent standard whereby the standard may revolve with respect to the lazy-tong, the clip connections of each standard being at points spaced from each other and from the ends of the standard. 70

2. In a luggage carrier of the type described, end standards, a lazy-tong structure intermediate the standards and composed of a series of pivotally connected levers, an intermediate standard having slots therein adjacent to the top and bottom thereof to slidably receive the connecting means between the ends of a pair of the levers of the lazy-tong structure permitting the latter to expand and contract in extension and collapse 85 of the same, means for clamping each standard to the running board of a vehicle, and means non-slidably connecting the ends of the lazy-tongs to the ends of the standard. 90

3. In a luggage carrier, a lazy-tong structure, standards at each end for supporting the lazy-tong structure upon the running board of a vehicle or the like, and means pivotally connecting the two free ends of the lazy-tong elements at each end of the structure to the adjacent standard at spaced relatively fixed points. 95

4. In a luggage carrier, a lazy-tong structure, standards at each end for supporting the lazy-tong structure upon the running board of a vehicle or the like, the lazy-tong structure being composed of a series of bars pivotally connected together intermediate their lengths, and a pair of connecting members intermediate each end of the structure 100 and the adjacent standard, each member being connected at one end to the lazy-tong structure and at its other end pivotally connected at a fixed point to the standard whereby to permit of relative movement between the free ends of the members of the lazy-tong structure at each end thereof incident to extension and contraction. 115

5. In a luggage carrier of the type described, end standards, means for clamping each standard to the running board of a vehicle, a lazy-tong structure intermediate the standards, and means to connect the lazy-tong structure with the standards comprising a pair of links pivotally connected to each end of the lazy-tong structure, each link having a pivot connection with its standard fixed against movement longitudinally of the standard. 120

6. In a luggage carrier of the type de- 130

scribed, end standards, means for clamping each standard to the running board of a vehicle, a lazy-tong structure intermediate the standards, and means to connect the lazy-tong structure with the standards comprising a pair of links pivotally connected to each end of the lazy-tong structure, each link having a pivot connection with its standard

fixed against movement longitudinally of the standard, the fixed pivot connection 10 above mentioned being such as to permit rotation of the standard with respect to the lazy-tong structure for folding purposes.

In testimony whereof I affix my signature.

GILBERT A. ROTH.
